UNITED STATES PATENT OFFICE.

JOSEPH BROCK, OF ERIE, PENNSYLVANIA.

HORSESHOE-PUNCHING MACHINE.

Application filed December 15, 1921. Serial No. 522,498.

The machine of this invention is designed to punch horse-shoe blanks, preferably doing all the punching at one operation. The machine also is designed to cut the blanks from a bar, to position the parts cut so as to properly punch them, to straighten the bar, and to upset it to lengths. The invention also relates to the details of construction and these and other features of the invention will appear from the specification and claims.

The invention is illustrated in the accompanying drawings as follows:

Fig. 1 shows a section on the line 1—1 in Fig. 2, parts being removed to better show construction.

Fig. 2 shows a front elevation of the machine.

Fig. 3 a section on the line 3—3 in Fig. 1. Fig. 3^a a face view of a cam for operating a feeding and clamping jaw.

Fig. 4 a section on the line 4—4 in Fig. 2.

Fig. 5 an end elevation.

Fig. 6 a central section of a centering device.

Fig. 7 an alternative construction showing the centering device.

Fig. 8 a front elevation, partly in section, showing an alternative construction of feeding device.

Fig. 9 a section on the line 9—9 in Fig. 8.

Fig. 10 a plan view of an alternative centering device.

1 marks the frame, and 2 and 3 bearings for the main shaft 4. A gear 5 is fixed on the shaft 4 and a gear 6 meshes with the gear 5. The gear 6 is fixed on a shaft 7 and the shaft 7 is carried in journals 8 in an extension of the frame. The shaft 7 is driven from a drive wheel 9, the device being provided with a fly wheel 9^a to carry the machinery through the punching action as is common in machines of this type. 10 is a feed table on which a blank A is fed into the machine. This table has the side guides 11 through which the blank passes. Rods 12 extend from the bracket 12^a to a post 13. These rods form the guide mechanism for the reciprocating feeding devices. A cross head 14 is slidingly mounted on the rods 12. This has an arm 15 to which a link 16 is attached. The link 16 has a forked end 17

which is pivotally secured to a collar 18 arranged between the shoulders 19 on an arm 20. The arm 20 extends from a ring 21 mounted in a wobbling driver 22. An arm 23 extends from the ring 21 through a slot 24 in a projection 25 of the frame. The wobbling head 22 is fixed on the shaft 4. It will readily be seen that as the head 22 is rotated the arm 20 is swung forward and back carrying the head 14 forward and back and thus through this reciprocating movement carrying the bar forward with each cycle of the machine. The head 14 has a bar guide 26 and two upwardly extending supports 27. A clamping dog 28 is fixed on a shaft 29 by means of a set screw 30. The shaft 29 is journaled in the supports 27. A lever 31 is fixed on the outer end of the shaft, the lever having a cam roller 32 at its lower end, which roller is engaged by a cam 33 on a bar 34 extending from the bracket 12^a. This engagement takes place near the forward end of the movement of the head to throw the clamping dog 28 out of engagement with the blank.

It will be noted that the blank is provided with the usual slot a in which holes are punched and also with the positioning notch b. After the clamping dog 28 is released, the bar is engaged by a point 36 on an engaging finger 35. The finger 35 is mounted on a shaft 37 extending between the brackets 38 at the front of the supports 27. This finger rides in its forward movement with the blank or bar being slightly back of a notch as the bar is engaged by the dog 28. Upon the release of this dog the finger picks up the notch and forces the bar forward, thus correctly positioning the bar for cutting off. In order to relieve the point 36 of engagement of the bar on the return movement a link 39 extends downwardly and is engaged by the pin 16^a connecting the link 16 with the arm 15. The arm 15 is provided with perforations 40 and the link 39 with perforations 41 whereby the starting and stopping points of the throw of the head 14 may be varied. The pin 16^a is smaller than the perforations 40 so that there is a slight slack or movement of the pin 16^a in the openings 40 and in consequence with the initial rearward movement of the head the

link 39 is drawn down lifting the finger 35 slightly off the bar. The bar is delivered through a sliding platform 42. A shear blade 43 is fixed on the forward end of the table 10 and a companion shear blade 44 is carried by the cross head 45. The cross head is U-shaped having downwardly extending arms 46 which have the guide edges 47 operating in the guides 48 in the frame, retaining plates 49 being arranged over the outside of the guides 48 to complete the guiding surface. Connecting rods 50 extend from the pins 51 arranged in the arms 46 to the eccentrics 52 fixed on the shaft 4. It will readily be seen that with each cycle of the machine or rotation of the shaft the cross head is reciprocated. A centering push rod 53 is mounted in the table 10, the forward end of this extending through an opening 54 in the shear blade 43. The push rod terminates in a head having a downwardly extending arm 55, the rear of the head extending into a guide-way 56 in the table 10. A rod 57 extends from the arm 55 through an opening 57^a in the post 13. The rod is screw-threaded at 58 and contact nuts 59 are arranged on the screw threads in the path of a forked arm 60. The arm 60 is pivoted on a pin 61 carried by the post 13. A push rod 62 extends from the lever 60 through a guide 63 on the extension 25 and terminates with a cam roller 64, the cam roller engaging a cam 65 on the end of the shaft 4. With each rotation of the shaft 4 therefore the push rod 53 is pushed forward centering the bar on the platform 42 and the push rod 53 is immediately returned so as to be brought out of the way by means of a spring 66.

After the bar reaches the platform 42 and is positioned by the rod 53 it is flattened and creased by the plate 67 having the creasing dies 67^a thereon. If the blank has been previously creased the dies correct any errors in the creasing and if not previously creased the creasing is done entirely by the dies. The straightening plate 67 is carried by pins 68 which extend into pockets 69 in the cross head 45. Shoulders 70 form guides in the pockets and springs 71 tend to force the plate downwardly, the downward movement being limited by the nuts 72 arranged on the cross head above the tops of the sockets. With the completion of the downward movement of the cross head the straightening plate engages the blank on the platform and exerts a straightening and crease-forming pressure, the pressure being measured by the strength of the springs. The platform 42 slides in guides 74 in the frame, the plates 73 being arranged on the platform below the guides so as to retain the platform in position. Guide plates 75 and 76 are mounted above the platform 42 in position to retain the blank under the flattening plate. The

guide bar 75 has openings 75^a into which the metal of the blank flows through the action of the creasing dies and thus an engagement is formed between the blank and the guide 75 which assures the stripping of the blank from the creasing dies. After the straightening and creasing movement above described and at the beginning of the return movement of the cross head the platform is actuated by the following mechanism:—a link 77 extends through a yoke 78. A spring 79 is arranged around the link 77 and a nut 80 forms the base of the spring on the link. A nut 81 is screwed on to the link on the outside of the yoke and thus permits of a yielding forward movement of the yoke but the connection draws the platform back with a backward movement of the yoke. The yoke is pivotally mounted on a lever 82. The lever is carried on a pin 83 mounted in brackets 84 on the frame. A connecting rod 85 is pivotally connected with the lever 82 and is provided with a slot 86 which extends over the shaft 4. The connecting rod has a roller 87 which extends into a cam slot 88 in the face of a cam wheel 89 locked by means of a key 90 on the shaft 4. The cam 88 is shaped to give to the platform the following movements:—Immediately after the lifting of the straightening plate 67 the platform is drawn rearwardly a sufficient distance to permit the bar retained between the guides 75 and 76 to drop off the front end of the platform on to the pins 91 so that the top of the bar resting on the pins will be below the bottom of the guide 76. The platform then goes forward, the front of the platform operating as a jaw carrying the blank with it to the position to be punched. The blank is first crowded against the front jaw so as to be straightened. The rear jaw then recedes slightly releasing the blank so that it may be adjusted endwise and then again grips the blank and holds it during the punching action. A dwell is then provided by which the clamping action is continued during the punching action. After the punching action is completed and the punches have receded the front jaw of the clamp is withdrawn and there is a slight forward movement of the platform kicking the blank off the die. The fast cam is then provided which draws the platform to the rear, this being the initial movement which is above described.

Pins 91 extend from the die plates at the front hereinafter described through brackets 91^a carried by the frame. These pins extend through the platform and are in position to receive the bar as the platform recedes and the blank is swept off the platform by the guide plate 76. The die 92 is in position to receive the blank as it is pushed forward by the jaw 93 at the front end of the platform and the blank is clamped be-

tween the jaw 94 and the front jaw 93. Just prior to this clamping action, however, and after the bar is brought to its position the blank is centered by a centering mechanism hereinafter described. A centering finger 95 has a detent 96 adapted to engage in the slots and this finger by its forward movement, there being one at each side of the machine, forces the blank to exactly central position. The finger 95 is carried by a swinging finger carrier 97, the finger carrier being pivoted on a pin 98, the pin 98 being mounted on the frame. The carrier 97 is provided with a cam bar 100, the cam bar having rounded ends which extend into the cam slots 101 carried by cam blocks 102 mounted on the arms 46 of the cross head. The cam slot has first a cam surface 101^a which with the downward movement of the cross head drops the finger 95. There is then a dwell 101^b in the cam slot which holds the finger in position as it is moved forward. There is then a return cam surface 101^c which lifts the finger out of the groove in the bar during the punching action and a dwell 101^d for the continued downward movement of the cross head while the punching takes place. While these fingers are thus depressed and lifted by the cam slot the finger is moved forward and positioned. The bar 100 is carried by a screw 103 by means of which it may be adjusted to adjust the height of the finger 95 and the adjustment is locked by a nut 104.

The finger is provided with an enlarged end 106 which is slidably mounted in a guide opening 107 in the carrier. A block 108 is adjusted in position by a screw 109. A pin 110 extends through the block 108 and cam rollers 111 are mounted on this pin, one at each side of the block and in the path of cams 112 which are arranged on the arms 46 of the cross head. The finger 95 has an extension 95^a which extends through a bracket 113 carried by the frame. A spring 114 is arranged on the extension 95^a and a nut 115 holds the spring in position. The spring opposes the cam 112 and returns the finger 95 at the completion of the operation of the cam upon it. In the operation of this device the finger is first lowered in the manner above described into position to engage the slot. The cam 112 then comes into operation and forces the finger forward so as to effect the centering operation. The finger is then raised by the cam 101^c and the forward movement is further extended so as to bring the point 96 of the finger out of the path of the punches. The finger is provided with a slot 95^b through which the punches can pass. After the punching operation the reverse of these movements takes place, the spring 114 returning the finger to the initial position. In order to strengthen the finger the carrier has a pro-

jection 105 which overhangs and engages the upper part of the finger.

I prefer while the straightening action is taking place by the clamp to up-set the ends of the bar so as to bring all the blanks to exactly the same length. This is accomplished by the following mechanism: A swage 116 is slidably mounted in a groove 117 in the frame. A spring 118 holds the swage in a rearward position. The rear end 75 of the swage is cam surfaced at 119 and this cam surface is in the path of a cam 120 carried by the arm 46. There is one of these mechanisms arranged for each side of the machine, the detail for one side being shown 80 in Fig. 6. It will be seen that with the downward movement of the cross head just after the bar is clamped so as to be held in position the ends of the blank are up-set sufficiently to bring all blanks to the exact 85 length. Punches 122 are arranged in a series of three or four depending on the shoe and are carried in punch blocks 123, the punches being secured therein by screws 123^a. The thrust on the punches is sustained by the 90 screws 124 extending through the block and the blocks are secured on the yoke by means of screws 125, these screws extending into slots 126 which permit of a slight adjustment 95 of the blocks. Different blocks may be used for different shoes.

Immediately following the punching action the front jaw 94 is depressed to permit the removal of the punched blank. The jaw is mounted on a jaw frame 127 which has the 100 guide edges 128, these edges operating in guides 129 on the frame and are held in place by the guide plates 130 secured to the face of the frame. A connecting block 131 is secured to the frame 127. A pitman 132 105 is connected to this block and is provided with a slotted yoke 133 which extends over the shaft 4. The connecting rod is connected with a cam roller 134 which operates upon a cam 135 fixed on the shaft 4, the cam being 110 locked on the shaft by a key 136. The connecting block 131 is secured to the frame by screws 138 and is supplied with an adjusting screw 137 so that the total upward movement 115 of the frame may be adjusted to vary the upper position of the jaw as desired. The cam 135 is shaped to drop the jaw immediately the punches recede from the blank and permit the platform to move forward to kick the blank off the dies. The cam 135 120 is provided with a dwell permitting the front jaw 94 to remain in its lower position long enough to accomplish this purpose when the cam again lifts the frame and puts the jaw in place for the next blank.

In the alternative construction shown in Fig. 7 the die 139 is made in two parts and is slidably movable and the punch carrier 140 is also slidably mounted, the two being connected by a post 141 through which a screw 130

142 extends into the die. The carrier is made in two sections, the opposing faces of the sections being provided with cams 143 which engage cams 144 carried by a bar 145, which engage cams 144 carried by a bar 145, the bar being secured by nuts 146 on a portion of the frame 147 and remaining stationary. As the punch carrier is reciprocated, it will be noted that the cams 143 and 144 operate upon each other and the sections of the punch carrier are separated. A spring 148 tends to draw the sections together. Punches 149 are fixed in the carrier sections. Punches 150 are slidably mounted in the sections, the upper ends of the punches extending through the sleeves 151 having shoulders 152 which limit the sliding movement of these punches. These punches 150 are held down yieldingly by a flat spring 153. In the operation of the device as the punches 150 reach the blank it is retained and with spring pressure on the blank the two are moved away from each other, one or the other of the punches 150 picking up a notch in the blank and carrying the blank to central position. After the blank is centered the continued movements of the punches complete the operation.

In the construction shown in Figs. 8 and 9 the bar is carried entirely into position opposite the punches by a feeding bar 154 which is moved by the cross head 14. This has a finger 155 adapted to engage a notch in the blank and this finger is pivoted on a pin 156 and is yieldingly pressed on the blank by a spring 157. In this structure there are two shears 44, one at each end, so that each blank is sheared to an exact length. This double shear may be used in connection with the upsetting if desired.

In the alternative construction shown in Fig. 10 the blank is centered by the cams 158 at the sides of the platform and as the bar is advanced.

What I claim as new is:

1. In a horse-shoe punching machine, the combination of a series of punches in alignment; a feeding device for a severed blank; a flattening device receiving the blank from the feeding device and operating on the blank to flatten the same; and a positioning device for advancing the blank from the flattening device to the punches.

2. In a horse-shoe punching machine, the combination of a series of punches in alignment; a bar feeding device; a shear for cutting the blank; a flattening device for flattening the blank after it is sheared; and devices for moving the blank from the flattening device into position relatively to the punches.

3. In a horse-shoe punching machine, the combination of a series of punches; a platform on which a blank is delivered; a flattening device acting on the platform for flattening the blank; a jaw in the front face of the platform; means moving the platform

and blank relatively to each other to drop the blank in front of the jaw; and means for actuating the jaw clamping the blank in punching position.

4. In a horse-shoe punching machine, the combination of a series of punches in alignment; a head carrying the punches; a flattening device carried by the head; means for delivering a severed blank under the flattening device; and means for carrying the blank from the flattening device to the punches.

5. In a horse-shoe punching machine, the combination of a series of punches; a flattening device; means for delivering a blank under the flattening device; a device for centering the blank relatively to the punches under the flattening device; and means for moving the blank from the flattening device to the punches.

6. In a horse-shoe punching machine, the combination of a series of punches; a flattening device; a shear; means for advancing a blank to the shear; means for positioning the blank under the flattening device; and means for moving the blank from the flattening device to the punches.

7. In a horse-shoe punching machine, the combination of a series of punches; a flattening device; means for advancing a bar to the shear; a positioning rod adapted to engage the end of a blank severed by the shear and to position the same under the flattening device; and means for moving the blank from the flattening device to the punches.

8. In a horse-shoe punching machine, the combination of a series of punches; a flattening device; a shear; a device engaging a blank operated upon by the shear and positioning the same under the flattening device; and means for moving the blank from the flattening device to the punches.

9. In a horse-shoe punching machine, the combination of a shear; a flattening device; a series of punches; a positioning rod extending through the shear in position to engage a severed blank and position the same under the flattening device; and means for moving the blank from the flattening device to the punches.

10. In a horse-shoe punching machine, the combination of a series of punches in alignment; and a feeding device for feeding a bar forward with relation to the punches comprising two instrumentalities, one operating upon surface peculiarities of the blank and the other gripping the blank.

11. In a horse-shoe punching machine, the combination of a series of punches in alignment; and means acting on the blank in position under the punches for giving to the blanks a uniformity of length.

12. In a horse-shoe punching machine, the combination of a series of punches; means

- for feeding a blank to position to be punched; and means for upsetting the blank to bring the blank to uniformity of length.
13. In a horse-shoe punching machine, the combination of a series of punches; a head carrying the punches; and means for upsetting the blank to bring the blank to uniform length, said means being actuated by the head.
14. In a horse-shoe punching machine, the combination of a series of punches; a swage arranged at the end of a blank positioning the blank relatively to the punches; and means for moving the swage inwardly against the blank and to bring the blank to a uniform length.
15. In a horse-shoe punching machine, the combination of a series of punches; a clamp operating on the blank under the punches; and a swage acting on the end of the blank for varying the length of the blank.
16. In a horse-shoe punching machine, the combination of a series of punches; a clamp operating on the blank under the punches; and a swage acting on the end of the blank for varying the length of the blank while engaged by the clamp.
17. In a horse-shoe punching machine, the combination of a series of punches; a head carrying the punches; a clamp holding the blank under the punches; a swage operating on the end of the blank; and mechanism operating the swage, said mechanism being actuated by the head.
18. In a horse-shoe punching machine, the combination of a series of punches; a head carrying the punches; a clamp holding the blank under the punches; a swage operating on the end of the blank; and a cam mechanism actuated by the head for actuating the swage.
19. In a horse-shoe punching machine, the combination of a creasing device; a punching mechanism comprising a plurality of punches in alinement; and means for automatically transferring a blank from the creasing device to the punching mechanism.
20. In a horse-shoe punching machine, the combination of a platform; a straightening and creasing die; means for operating the straightening and creasing die against the blank; a punching mechanism; and means for automatically transferring the blank from the platform to the punching mechanism.
21. In a horse-shoe punching machine, the combination of a platform; a creasing die adapted to operate on a blank on the platform; means for engaging the blank to strip the same from the creasing die; a punching mechanism; and means for automatically conveying the blank to the punching mechanism.
22. In a horse-shoe punching machine, the combination of a creasing die; means for feeding a blank to position relatively to the creasing die; means for actuating the creasing die; a punching mechanism comprising a plurality of punches; and means for automatically conveying the blank from the creasing die and positioning the same relatively to the punching mechanism.
23. In a horse-shoe punching machine, the combination of a creasing die; means for cutting off a blank; means for positioning the blank under the creasing die; means for actuating the creasing die; a punching mechanism comprising a plurality of punches; and means for automatically conveying the blank from the creasing die to the punches.
24. In a horse-shoe punching machine, the combination of a punching head; a series of punches carried by the head; means for actuating the head; a clamp for holding the blank to be punched, said clamp comprising a jaw adapted to straighten the blank as it is brought to initial position; means for actuating one of the jaws to release the blank momentarily; and means for positioning the blank during the interval of release.
25. In a horse-shoe punching machine, the combination of a reciprocating platform, the front edge of which forms a clamping jaw; guides above the platform; means for feeding a blank in position between the guides; a creasing die operating upon the blank between the guides; means for actuating the platform to recede and permit the blank to drop in front of the platform; means for advancing the platform to carry the blank to punching position; and a punching mechanism operating on the blank so positioned.
26. In a horse-shoe punching machine, the combination of a platform; a guide on the platform having side openings therein; and creasing dies adapted to operate on the blank, the openings receiving the flow of metal under the action of the creasing dies to strip the blank from the creasing dies as the dies recede.
27. In a horse-shoe punching machine, the combination of a creaser; and shears cutting the blank at each side of the creaser.
28. In a horse-shoe punching machine, the combination of a creaser; shears cutting the blank at each side of the creaser; and means for punching the blank.
29. In a horse-shoe punching machine, the combination of a series of punches; and shears cutting the blank at each end centering the severed blank with the punches.
30. In a horse-shoe punching machine, the combination of a series of punches; and a pair of shears severing a blank from a bar and cutting the opposite end of the blank to center the severed blank with the punches.
31. In a horse-shoe punching machine, the combination of a series of punches; shears

cutting the blank at each end centering the severed blank with the punches; and means for moving the blank so centered to the punches.

5 32. In a horse-shoe punching machine, the combination of a series of punches; a pair of shears severing a blank from a bar and

cutting the opposite end of the blank to center the severed blank with the punches; and means for moving the blank to the punches.

In testimony whereof I have hereunto set my hand.

JOSEPH BROCK.
